OVERHEAD TOOL SUPPORT

Thomas C. Robertson, deceased, late of National Park, N. J., by Julia C. Robertson, administratrix, National Park, N. J., and Harry N. Conard and Joseph Richards, Philadelphia, Pa.

Application April 10, 1943, Serial No. 482,663

1 Claim. (Cl. 78—46)

(Granted under the act of March 3, 1883, as amended April 30, 1928; 370 O. G. 757)

This invention relates to a support for an overhead pneumatic tool and has as an object to provide an improved stand or support especially intended for holding a pneumatic tool such as a pneumatic riveting device or a pneumatic hammer or chisel in an operative position when working in an overhead location.

A further object of this invention is to provide a means for supporting a pneumatic tool when it is in operation on any overhead structure such as against a ceiling or roof or the bottom of a vessel under construction or in drydock.

Pneumatic tools such as pneumatic riveting devices and pneumatic hammers, even in the smaller sizes, are usually of considerable weight, in the neighborhood of 75 pounds or more. It is physically impossible for an operator to hold such a tool in his hands and operate efficiently for any considerable period of time. It has, therefore, been customary to provide a mechanical supporting device for the pneumatic tool during overhead operation of any considerable length of time. In shipbuilding, for instance, it has been customary to support the pneumatic tool by a supporting device suspended through the bottom of the ship as, for instance, from an adjacent bolt or rivet hole. This, however, has several disadvantages, among which are the fact that the rivet hole may not be convenient for the particular operation and further due to the great loss of time involved when it becomes necessary to shift the tool support from one location to another as the work progresses, for in such cases it is necessary to send a helper into the ship in order to release the supporting device from its depending rivet hole and then have him try and locate another rivet hole adjacent to the progress of the work.

With the present invention, such disadvantages are eliminated, for the support of this invention operates without the necessity of any convenient or pre-existing rivet hole and therefore without the necessity of using a helper inside of the vessel under construction. Instead, this invention includes a support which cooperates with the bottom of the overhead structure and the floor therebeneath, yet, nevertheless, is movable to any desired location as needed and then is easily adjusted in its new location to provide a firm foundation for the operation of the riveting tool.

With the foregoing and other objects in view, as will hereinafter become apparent, this invention includes the construction, combination and

arrangement of parts hereafter more fully set forth and described and illustrated on the accompanying drawing, in which,

The figure is a perspective view of the stand or support of this invention in operative position.

There is shown at 10 the stand or support of this invention in operative position, showing the pneumatic tool, in this case a pneumatic riveting device 11 positioned for operation on a rivet 12 in a plate 13 forming part of the bottom of a ship in the process of construction, the usual pneumatic power supply hose 14 having been attached to the handle 15 of the riveting tool 11. This riveting tool 11 is provided with a pair of opposite extending pins 16 which may rest in a selected pair of recesses 17 on the bifurcations of a yoke 18 being mounted on the end of a rod or pipe 20.

The pipe 20 is supported between two pairs of pipe supporting rollers 21 and 22. The rollers 21 are journaled in a box 23 from the bottom of which extends a shaft 24 into a swivel base 25. The rollers 22 are journaled in a box 19. This swivel base 25 is provided with a recess to receive the shaft 24 and one side of the recess is slotted and provided with a pair of protuberances 26 through which extends a wing bolt 27 for drawing the protuberances together and thus causing the swivel base 25 to securely grip the shaft 24. Integrally extending from one side of the swivel base 25 is a swivel arm 28 whose end 30 is apertured to receive a post 31 on which is supported a U in which the rollers 22 are journaled. The apertured end 30 of the swivel arm 28 is provided with a transverse opening 32 while the post 31 which carries the box 19 and rollers 22 is provided with a plurality of transverse openings 33, whereby the post 31 may be supported at any desired position to hold the box 19 and its rollers 22 at any desired height relative to the rollers 21 by inserting a pin through the apertures 33 in the post 31.

To keep the rollers 21 and 22 in proper alignment, the roller box 23 for the rollers 21 is provided with a depending bifurcated toe 34 which extends over the upper edge of the swivel arm 28. The swivel base 25 rests on an inverted U 35 which is welded to a base plate 36. The base plate 36 is provided with a central aperture to receive the open end of the shaft 37, the shaft 37 and the box shaft 24 being vertically aligned. This shaft 37 is provided with an enlarged knob 38 swivelly supporting the plate 36 thereover, thus permitting a swivelling of the swivel base

25 as needed. Below knob 38, the shaft 37 is threaded as at 40 so that it may be adjustably secured between nuts 41 and 42 on a head plate 43 of the quadrupod 44.

This quadrupod 44 is also provided with a shelf 45 which, together with the head plate 43, serves to keep the four legs in rigid relation to each other. Each of the four legs of this quadrupod 44 are hollow so as to receive a telescopic extension leg 46 therein. Each of the extension legs 46 is provided with a plurality of pairs of holes 47, any pair of which may be aligned with a pair of holes in the lower end of the quadrupod legs and held in such a selected position by means of a pin 48 therethrough, thus making the entire quadrupod adjustable both as to height and to contour of the supporting floor 50. The top of the roller box 23 is provided with an upwardly extending screw 51 on which is threaded a sleeve 52 to the top of which is swivelled a hand 53, as by a ball and socket arrangement at 54.

In operation, the stand or support 10 is set up in any desired location with the legs 46 so adjusted as to bring the hand 53 somewhat close to the bottom of the ship plate 13 that is being riveted. A finer adjustment may then be made by suitably moving the nuts 41 and 42 on the supporting shaft 40 through the head plate 43. The last fine adjustment may then be made by rotating the sleeve 52 on shaft 51 so as to cause the hand 53 to jam against the bottom of the hull plate 13. The rod or pipe 20 is inserted between the aligned pairs of rollers 21 and 22 which may be swivelled to place the rod yoke 18 so as to support the riveting tool 11 in any desired location. Obviously, by thus swivelling the device and pushing the rod or pipe 20 back and forth through the rollers, a considerable area of the hull plate 13 may be reached with a single location of the support or stand 10. The riveting tool 11 is placed on the selected pair of supporting yoke recesses 17 and then operated in the customary manner. By means of the throttle valve 55 and its conventional yieldable sleeve 56, the operator merely withdraws the hammer against the spring sleeve to permit the tool to be placed over the desired rivet 12 and then opens the valve 55 which sends the riveting hammer against the rivet with no lifting effort on the part of the operator. When this particular rivet is completed, the throttle valve is closed and the riveting tool pulled against its yieldable sleeve 56, releasing it from that rivet and then the pipe 20 is swivelled or rolled, or both, to reach the next rivet to be operated on

in a similar manner. When all the rivets within range are completed, the entire support or stand may be easily shifted to another area to bring a new group of rivets within range, the support being adjusted as needed to fit the new location.

Other modifications and changes in the number and arrangement of the parts may be made by those skilled in the art without departing from the nature of this invention within the scope of what is hereinafter claimed.

The invention described herein may be manufactured and used by or for the Government of the United States of America for governmental purposes without the payment of any royalties thereon or therefor.

Having thus set forth and disclosed the nature of this invention, what is claimed is:

An overhead tool supporting stand, said stand 20 including a multipod base, said multipod base having extendable legs telescopically adjustable thereon at a desired height, a shelf providing a bracing member between said legs, a platform securing the tops of said legs together, a shaft 25 adjustably secured on said platform, a base member swivelly supported on said shaft, a second shaft mounted in said swivelled base member and axially aligned with said first-mentioned shaft, a box member mounted on said second- 30 mentioned shaft in fixed relation to said swivelled base member, a pair of pipe rollers, one above the other, journaled in said box member, an adjustably secured overhead pressure member mounted on said roller supporting box member, 35 adapted to be braced against an overhead piece of work against which the tool is to be operated, a swivel arm integrally extending from said base member in a horizontal direction, an adjustably secured roller supporting box member mounted on said swivel arm, a pair of roller members journaled in said latter box member, one above the other, a rod slidably mounted on said two 40 pairs of roller members and a tool carrying bifurcated yoke member secured at one end of said rod whereby the tool carried by said yoke member may be moved horizontally by sliding said rod and may be moved vertically by adjusting said second-mentioned roller supporting box member.
